LATCHING MEANS FOR DIE SET RETAINERS

William J. Blazek, New Lexington, Ohio, assignor to Lempco Products, Inc., Bedford, Ohio, a corporation of Ohio

Application November 8, 1955, Serial No. 545,694

8 Claims. (Cl. 164—118)

This invention relates to guide appliances for the die sets of punch presses and other reciprocatory machine tools.

A punch and die set is an assembly consisting of an upper member called the punch holder or plate and a lower member called the die holder or plate. The lower or under surface of the punch holder and the upper or top surface of the die holder are those on which the punch and die sections of a finished punch press tool are mounted, although these positions are sometimes reversed. In use, the die holder is clamped to the bed or bolster plate of the punch press, while the upwardly extending punch holder shank is fastened in the clamping hole provided therefor in the sliding punch press ram. The tool is actuated by the reciprocating motion of the ram. Mating guide posts and bushings of an assembled die set assist in maintaining tool alignment during die setting and the operation of the tool in the punch press.

These guide posts and bushings are employed in maintaining the punch and die details in true alignment or registry during ram-produced reciprocatory movement of the punch and punch holder relative to the die and die holder. In conventional constructions, the posts are of plain cylindrical formation and are carried by and depend rigidly in relatively spaced order from associated punch holders. These depending posts are received and have a close working fit in longitudinal holes or bores formed in cooperative die holder mounted stationary bushings. The operation, longevity and accuracy of such plain guide posts and bushings have been improved by interposing pressure-loaded antifriction bearings between annularly spaced surfaces of the posts and bushings, as disclosed in the prior patent to Connor, No. 2,422,774, granted June 24, 1947.

In such antifriction guide devices, die alignment is obtained by providing one of the holders, usually the punch holder, of a die set with a bushing having a cylindrical bore formed therein for receiving a cylindrical coaxial post provided on the other holder when relative movement of the holders during working strokes of the press takes place. Undesired lateral motion in such guide devices is precluded by providing each device with a tubular retainer or sleeve carrying a plurality of spaced ball elements of uniform diameter, each of the elements having a diameter slightly greater than the width of the annular space formed between the post of the appliance and adjacent inner cylindrical surface of the bushing bore receiving the post.

While such die set guide assemblies provide for high accuracy in die alignment or registry, yet certain difficulty has been encountered, particularly on the part of inexperienced assemblers, in properly positioning the ball-bearing retainers so that they will be disposed for unobstructed sliding movement between associated post and bushing members in the normal stroke movements of the press, and at the same time to maintain the retainers throughout such stroke movements in positions in which

2

at least certain of the ball bearings therein are disposed under compressive loading forces.

Accordingly, it is an object of the invention to provide an antifriction guide assembly for die sets wherein improved means are provided for effecting proper positioning of the bearing-carrying retainers of such guide assemblies, whereby to cause the retainers to be maintained in alignment-producing and antifriction engagement with associated stationary and movable guide members.

Another object of the invention is to provide an improved guiding and alignment-maintaining assembly for machine press die sets having movable bearing-carrying retainers disposed in coaxial relation with interfitting stationary and movable guide members, and wherein positive and simplified means are provided for maintaining such retainers, at all stages of relative movement of said members, in predetermined operative order with respect to said members, whereby to maintain at least certain of the bearings of said retainers under confined conditions of compressive loading and yet to permit the same to move longitudinally of the guide assemblies concomitantly with the movable members thereof but at a different rate of linear speed.

A further object is to provide the ball-bearing-carrying retainers of such guide assemblies with yieldable stop means adapted for engagement with associated stationary members of the assemblies, whereby to determine proper initial operating positions of the retainers in admitting of antifriction retention thereof in association with the interfitting stationary and movable members of the assemblies throughout their operating strokes, said stop means being automatically retractable to assume inactive positions when engaged by said members during periods of relative longitudinal movement therebetween.

For a further understanding of the invention, including additional objects, constructional and operational features and advantages thereof, reference should now be had to the following description and accompanying drawing, wherein:

Fig. 1 is a view partly in side elevation and vertical section of an antifriction guide assembly for machine press die sets, and illustrating the bearing retainer stop and locating means of the present invention incorporated therein;

Fig. 2 is a fragmentary detail vertical sectional view disclosing on a greater scale one of the enlarged ball-bearing-receiving seats of an antifriction guide assembly retainer formed in accordance with the present invention, and showing the ball-bearing occupying an enlarged seat resiliently displaced in an outward direction for retainer-holding engagement with the upper shoulder-forming edge of an associated bushing;

Fig. 3 is a similar view showing a structural variation of the form of the invention depicted in Fig. 2, and wherein in a stop-forming ball-bearing of the guide assembly sleeve is resiliently displaced in an inward direction for post engagement instead of an outward one of bushing contact;

Fig. 4 is a view similar to Fig. 1 and illustrating another modified form of the present invention, wherein the stop means for indexing the operative positions of the bearing-retaining members comprise spring-pressed post shoulder-engaging catch devices separate from the bearings of the sleeve members;

Fig. 5 is a fragmentary detail vertical sectional view on an enlarged scale of one of the catch devices of Fig. 4 and associated parts;

Fig. 6 is a detail plan view of a resilient split ring or band adapted for use in connection with the foregoing stop and positioning determining devices.

Referring to the drawings by numerals, and more particularly to the disclosure contained in Figs. 1 and 2, the movable punch and stationary die holders 10 and 11,

respectively, of a die set, are provided with one or more antifriction guide assemblies 12. The latter are employed for maintaining the holders 10 and 11, and parts carried thereby, in proper alignment or positions of relative registry during working movements of a punch press, or other machine tool, on which such a die set is mounted.

In this instance, each assembly is shown as comprising a cylindrical bushing 13 rigidly carried by and arising from an opening formed in the die holder 11 of the die set. The bushing provides an internal cylindrical bore 14 of uniform diameter throughout its length, the bore having machined, ground, hardened and/or polished wall surfaces held to close dimensional tolerances. The movable plate 10 of each assembly carries a fixed, rigid, depending pin or post 15 having cylindrical outer wall surfaces of uniform diameter substantially throughout the length thereof, these surfaces being held within close dimensional limits by machining and otherwise finishing and hardening the same to a true cylindrical contour.

Mounted for linear movement in each guide assembly is a tubular, sleeve-like, bearing retainer 16, the latter having accurately finished inner and outer cylindrical surfaces of uniform diameter hardened, polished or otherwise treated after the manner of forming the complementary surfaces of the post and bearing members. Each retainer is formed with a plurality of transverse relatively spaced openings 17 constituting seats for the rotatable retention of a plurality of ball-bearing elements 18. The wall thickness of each retainer is less than the radial width of an annular space 19 formed between each interfitting pair of guide bushings and posts when the latter are disposed in relatively telescoped order. Each bearing element, however, possesses a diameter slightly greater than the radial width of the space 19 receiving the same. This enlarged diameter is important in the operation of guide appliances of this character, in that when a post 15 descends so that its lower end is positioned in the upper part of the inner bore 20 of an associated retainer, and at the same time in the upper part of the bore 14 of an associated guide bushing 13, certain of the ball bearing elements will be engaged by the post and crowded thereby into engagement with the inner bushing wall to place the post-engaged ball elements of the sleeve under compressive forces. The ball elements so engaged are rotated, with the result that the retainer moves downwardly concomitantly with the descending post, but at a lower rate of linear travel. Such motion is continued as the ball elements are progressively engaged by the descending post, producing a positive guiding action wherein lateral motion is eliminated and accuracy thereby obtained in punch and die registry.

One of the difficulties hitherto encountered in the use of these desirable guide appliances in die sets is that of positioning the floating retainer 16 so that it maintains at all times a proper working relationship with the movable and stationary members of the die set, which members have been here shown as comprising the movable post 15 and the stationary bushing 13, although this order might be reversed if desired.

When the post 15 is elevated to assume a starting position, the lower end thereof is preferably positioned so that it does not confine one or more bearings 18 by applying compressive forces thereto. Under these conditions of relative release and to prevent the retainer from dropping gravitationally into the bushing bore 14, certain of the bearings 18, those here shown at 18a, are disposed in horizontal order for contact with the upper shoulder-forming edge 20 of the bushing. The bearings 18a are pressed outwardly and radially of the retainer body by lateral movement in the enlarged openings constituting the seats 17a. The relatively enlarged inner ends 17b of the openings 17a communicate with an annular groove 21 in which is positioned a split resilient ring or band 22. When actively positioned in the guide assembly to occupy the enlarged inner ends 17b of the seats 17a

and the groove 21, the ring or band 22 is in a somewhat circumferentially contracted state so that its expansive energy is directed outwardly on the ball elements 18a, causing the latter to be seated in the relatively restricted outer portions of the seats or openings 17a. This is done so that the elements 18a will be maintained in contact with the shouldered edge 20 with sufficient firmness to sustain the weight of the retainer and to prevent its dropping into the lower part of the bushing bore 14.

As the post 15 descends from its elevated position at the start of its working stroke, the same moves into pressure-loading contact with the ball elements 18 disposed immediately below the elements 18a. Since the elements 18 cannot move radially outwardly of the retainer after 15 the manner of the elements 18a, but are confined positively in their seats against such radial movement, and are, also, additionally held by pressing against the wall surface of the bore 14, it will be evident that the ball elements 18 so engaged are positively rotated and placed 20 under loading compression by the descending post. The positive rotation thus imparted to the compressively loaded ball elements causes the retainer to descend and move 25 simultaneously with the post but at a lower rate of travel, thus overcoming the action of the spring 22 in causing the ball elements 18a to move radially inwardly to clear the shoulder 20.

Under these conditions, the support of the floating retainer no longer depends on the engagement of the spring-pressed ball elements 18a in contacting the bushing shoulder or edge 20, but such supporting function is borne by 30 the tight compression-producing forces which the descending post develops for application to the ball elements 18 and the walls of the bore 14. The retainer is thus caused to travel in about one to two ratio with 35 the post as the latter moves either downwardly or upwardly on its working strokes, so that the spring-pressed ball elements 18a do not again support the retainer until the post has reached its full upward position of travel, at which time the above-defined cycle may be repeated.

In the form of the invention illustrated in Fig. 3, the same features of control and operation are essentially present, but in this form the ball elements shown at 18b are forced inwardly and radially of the retainer 16 by 40 the action of the resilient ring or band 22. In this construction, the retainer is supported from the lower end of the post 15 when the latter occupies its elevated position through engagement with an annular recess or groove 23 formed in and extending around the lower part of the post. The openings 17b of the retainer 16 in this latter 45 form of my invention are oppositely formed or disposed with respect to the openings 17a so that the relatively enlarged regions of the openings 17b are disposed toward the outside of the retainer rather than the inner side thereof.

In the construction disclosed in Fig. 3, when the post descends on its working stroke the ball elements 18b are 50 displaced outwardly, thus releasing the associated retainer from its association of suspended support from the lower end of the post. However, at this time the 55 descending post engages ball elements 18 disposed immediately below the elements 18b, thereby placing the engaged elements 18 under compression and causing regulated descent of the retainer at a lower rate of travel than the descending post, as previously explained. When 60 the post returns to its elevated position after completing its cycle of movement, the ball elements 18b are again seated in the recess or groove 23 to support the retainer or sleeve.

Another variation of this construction is disclosed in 65 Figs. 4 and 5 wherein the annular groove 24, formed in the bottom portion of the post 15, is provided with a shoulder 25 for engagement with the inner beveled ends of a plurality of radially positioned latch members 26. These members are slidably mounted in the openings 70 17c, and are pressed inwardly toward seated engage-

ment with the post groove 24 and its shoulder 25 by the spring ring 22, the latter being seated in notches formed in the outer ends of the latch members. It will be evident that with the use of this construction, when the post descends on its working stroke, the engagement of the conical wall surfaces of the groove 24 with the inner ends of the latch members 26, results in outward radial movement of the latch members against the resistance of the spring ring 22. The sleeve is thus released for controlled downward movement with the post as the post engages the ball elements 18 to impart compressive loading thereto.

Through the use of the means described, or the equivalent thereof, the vertically movable ball-bearing-carrying retainer or sleeve members of antifriction die set guide assemblies are positively supported or retained against movement in a predetermined positional relation to the associated movable and stationary members of the guide assembly. Further, the construction of the positioning means of the present invention is such that the retainer-supporting function thereof is released or removed automatically with the descent of the moving member of the assembly on its working stroke, so that the retainer member will be caused positively to move linearly with the associated movable member at a controlled relative rate of travel throughout the full working stroke of said movable member. When the latter returns to its normal or starting position the retainer member returns with it and occupies a predetermined positional relationship therewith. At this time the ball elements of the retainer member are relieved of the compressive forces resulting from their simultaneous contact with contiguous surfaces of the movable and stationary guide members of the assembly. The telescopic relation between the guide members during a working stroke and the interposition of the retainer member with its ball elements, enables the retainer member to be movably positioned in its established relation with said guide members. The retainer, it will be observed, moves in unison with an associated post when the bearing elements are unloaded, but when said elements are loaded or pressure confined between the post and bushing, the post-carried retainer holding means are released to admit of independent relative movement of the retainer with respect to the post, or other movable member normally carrying the same.

Various other modifications may be made within the scope of the following claims, including the employment of posts of square or polygonal cross-sectional formation and roller bearing elements rather than ball bearing elements. Also, dual walls of sheet metal may be used in the formation of the retainers rather than the solid wall types shown.

I claim:

1. Guide mechanism for the die sets of presses, comprising: a stationary member; a movable member disposed in coaxial order with the stationary member and movable longitudinally into and out of interfitting relationship therewith; a retaining sleeve occupying an annular space formed between said members when the latter are disposed in interfitting order; ball elements rotatably movable in socket-forming openings provided therefor in the wall of said sleeve and having antifriction guiding engagement with the adjacent wall surfaces of said members defining said space, said elements when in simultaneous contact with said member surfaces being placed under compression loading whereby to cause said sleeve to travel linearly concomitantly with and at a controlled rate relative to that of the associated movable guide member; and means for positively supporting said sleeve in a fixed predetermined positional order with respect to said movable and stationary guide members when the movable member assumes a position removing the same from compressive engagement with the ball elements.

5 2. Latching means for die set guiding and aligning appliances of the type embodying interfitting stationary and movable guide members, there being a floating ball-bearing retaining sleeve movably interposed between said members, the bearings of said sleeve receiving compressive loading through opposing simultaneous contact with said members during working movement thereof; and retractable latch means for supporting the sleeve of said appliance in a definite positional order in relation to said members when support normally afforded said sleeve through compressive loading of said bearings is removed as a result of change in relative positions of said members.

15 3. Alignment maintaining antifriction guide means for die sets, comprising: relatively movable axially arranged socket and post members; a sleeve formed for movable interposition between said socket and post members when the latter are disposed in interfitting order; ball bearings rotatably positioned in spaced seat-forming 20 openings provided therefor in the cylindrical wall of said sleeve, said bearings being of uniform diameter and arranged in said sleeve openings to project equidistantly beyond the inner and outer wall surfaces of the sleeve for simultaneous compressive contact with adjacent wall 25 surfaces of said socket and post members during interfitting longitudinal movement of one of said last-named members with respect to the other, whereby to produce movement of the sleeve in a linear direction concomitantly with relative movement between said members; 30 and means operative when said members attain relative positions in which the bearings of said sleeve are relieved of sustaining compressive forces produced by simultaneous contact of said bearings with said members to effect the support of said sleeve in a definite operational position relative to said members.

35 4. Alignment maintaining antifriction guide means for die sets, comprising: relatively stationary and movable axially arranged socket and post members; a sleeve positioned for longitudinal movement between the post and sleeve members, said sleeve being formed with spaced 40 openings for the rotatable reception of ball elements, the latter being of such diameter as to engage simultaneously adjacent wall surfaces of said members and thereby to pressure load said elements compressively during relative interfitting working movements on the part of said members, such loading causing said sleeve to move linearly with the movable member at a proportioned rate of travel; and movable latching means carried by and cooperative with said members and sleeve to sustain the 45 latter against movement in a definite position in relation to said members when the latter occupy a relative order relieving said elements of their compressive loading.

50 5. Die set aligning and guiding means as defined in claim 4, and wherein said latching means are disposed 55 radially of the guide means and have releasable engagement with the movable guide member when the latter is advanced on an operating stroke.

60 6. Die set aligning and guiding means as defined in claim 4, and wherein said latching means comprises at least one of said ball elements positioned in the opening provided therefor in said sleeve for radial movement; and resilient means positively displacing the latching ball element radially to maintain the same in a position in which it protrudes yieldably on one side of the sleeve to a greater extent than the remaining ball elements, said protruding ball element having releasable sleeve-supporting contact with one of said guide members when the latter occupy relative positions in which said ball elements are relieved of compressive loading.

65 7. Die set aligning and guiding means as defined in and by claim 4, and wherein said latching means includes in said sleeve an enlarged seating opening for the reception of at least one of said ball elements, said seating opening enabling the ball element positioned therein to 70 protrude outwardly and laterally from a side of said

sleeve to a greater extent than remaining ball elements when the post and socket members occupying relative positions in which said sleeve-carried ball elements are relieved of compressive loading; and resilient means cooperative with the protruding ball element to maintain the same, in the absence of preponderant opposing forces, in its position of maximum protrusion in which said element engages one of said members in retractable sleeve-supporting relation.

8. The combination with antifriction die set guiding and aligning means, said means being of the type embodying a bushing member carried by one of the plates of a die set and having a bore arranged to receive axially a post member carried by another die set plate, said members being relatively movable to cause the post member to move into and out of the bore of said bushing member,

there being a floating sleeve arranged for relative movement longitudinally and axially of and between said member, the cylindrical wall of said sleeve being formed with seating openings for the reception of a plurality of ball elements which protrude from opposite sides of the sleeve wall for simultaneous contact with adjacent wall surfaces of said members when the latter are arranged into interfitting order; and resiliently projected latch means movably carried by said sleeve and operative when 10 said members are in predetermined relative order to engage yieldably shoulder means provided by one of said members, whereby to retain said sleeve in a stationarily supported position in dwell periods existing between working movements of said members.
